UNITED STATES PATENT OFFICE.

GEORGE SANDERS, OF BURTON-UPON-TRENT, ENGLAND.

CASK-TILTER.

SPECIFICATION forming part of Letters Patent No. 748,658, dated January 5, 1904.

Application filed September 4, 1903. Serial No. 172,015. (No model.)

To all whom it may concern:

Be it known that I, GEORGE SANDERS, a subject of the King of Great Britain and Ireland, and a resident of 63 Varlow street, Burton-upon-Trent, in the county of Stafford, England, have invented a certain new and useful Improved Cask-Tilter, of which the following is a specification.

The objects of my invention are to provide a cask-tilter that will tilt or accommodate all sizes of casks, will work equally well on brick, wood, stone, or other thralls, and which may be operated quite smoothly, so as not to disturb the contents of the cask.

15 The drawing, which forms a part of this specification, represents my improved device in perspective applied to the under side side of one end of a cask.

The device is preferably constructed of wrought-iron and has two upright bars $a a'$, secured to two fixed cross-bars, one at the top b and one at the bottom e . I also provide a movable cross-bar c , working up and down on a screw f between the top and bottom fixed cross-bars. This movable cross-bar c works on the two uprights $a a'$, which fit in the said movable cross-bar c in slots c' and c^2 , the said slots being specially made to receive the uprights, so as to permit them to 25 work freely in the said slots. The slots and uprights need not necessarily be of the section shown. The screw f is turned by a hand-wheel g at the top and is secured in the lower cross-bar e at e' in such a manner that it may 30 work freely in the said slots. The slots and uprights need not necessarily be of the section shown. The screw f is turned by a hand-wheel g at the top and is secured in the lower cross-bar e at e' in such a manner that it may 35 not be detached, but may turn round when operated by the hand-wheel g .

To the movable cross-bar c are fixed two arms $d d'$ by any suitable means, such as by stout bolts and nuts. Affixed to the ends of 40 the said arms $d d'$ is a cross-arm h , preferably curved to receive the end of the cask l . The two arms $d d'$ are of sufficient length to permit the cross-arm h to hold the cask l in such a manner that it will not fall when be-

ing raised, and to assist in this the said 45 cross-arm may also have small teeth on the external edge thereof, if required, the said teeth to aid the cross-arm h to retain the cask in position. These teeth are not, however, shown upon the drawing. On the screw 50 f being turned by the hand-wheel g the movable cross-bar c will rise on the uprights $a a'$ and raise the arms $d d'$ and cross-arm h , affixed thereto, and the cask l , resting on the said cross-arm, to any height required 55 until the movable cross-bar c reaches the fixed cross-bar at the top b .

The device is supported by feet $k k'$, affixed to the lower ends of the uprights, said feet being of a sufficient size to prevent the 60 machine falling forward while at work.

The different parts of the device may be joined by screws or in any other manner, if required, and may be made in any size.

The device may either be placed on the 65 same or on a different level to the cask, as may be found most convenient.

Having now described my invention, what I claim as new, and desire to secure by Letters Patent, is—

In a cask-tilter, in combination a frame 70 comprising uprights, a threaded bar carried thereby, means for turning the threaded bar, a movable cross-piece sliding on uprights of the frame, the said threaded bar passing 75 through and adapted to raise and lower the movable cross-piece, bars extending horizontally from the cross-piece and a support for the cask carried by the said bars, said support being shaped to conform to the side of 80 the cask, substantially as described.

In witness whereof I have hereunto set my hand in presence of two witnesses.

GEORGE SANDERS.
